UNITED STATES PATENT OFFICE.

FOREST L. GRAY, OF KENMORE, OHIO.

REISSUED

1,395,104.

Specification of Letters Patent.

Patented Oct. 25, 1921.

Application filed April 26, 1920. Serial No. 376,740.

To all whom it may concern:

Be it known that I, FOREST L. GRAY, a citizen of the United States of America, residing at Kenmore, in the county of Summit 5 and State of Ohio, have invented new and useful Improvements in Hair-Clippers, of which the following is a specification.

This invention relates to improvements in clippers especially designed for barbers' use 10 and has for an object the provision of means whereby the length of the hair being cut may be regulated.

Another object is the provision of means 15 for preventing the clippers from sticking to the neck of a person, due to the moist condition of the skin or the formation of a vacuum beneath the bottom of the clippers.

Another object is the provision of a device 20 of this character which may either be manufactured with the clipper or separately made and attached thereto.

Other objects and advantages of the invention will appear as the following description is read in connection with the accompanying drawings.

In the drawings:—

Figure 1 is a side elevation of a pair of clippers embodying the invention.

Fig. 2 is a bottom plan of the base plate.

Fig. 3 is a transverse sectional view of the same.

Referring in detail to the drawings, wherein like characters of reference denote corresponding parts, the clipper which is 35 designated in its entirety by the reference character 10 includes a base plate 11. This base plate may be secured to a plate 12 which carries the comb teeth through the medium of fastening devices 13, so as to permit of its 40 attachment to clippers of various makes.

The plate 11 has extending from the bottom thereof in right angled relation, a plurality of spaced blades 14, the forward ends of these blades being pointed and disposed

adjacent the forward edge of the base plate 45 11 and extending substantially throughout the length of the plate. The outer edges of the blades 14 are convex in shape and provide runners upon which the clipper may be rocked to regulate the length of the hair 50 being cut. The forward ends of the blades are arranged adjacent the rear ends of the comb teeth and if desired the plate 11 may be provided with extending teeth 15 with their notches registering with the notches 55 between the comb teeth.

Extending from the bottom of the base plate 11 are spaced pairs of teeth 16 which are also provided with convexed lower edges and have their forward pointed ends 60 alined with the ends of the teeth 14. These teeth together with the teeth 14 provide for the separation of the hair and prevent the formation of a vacuum beneath the bottom of the base plate. If desired, the blades 14 65 and 16 may be connected directly to the base plate 12 in the manufacture of the device.

The invention is susceptible of various changes in its form, proportions and minor details of construction and the right is here- 70 in reserved to make such changes as properly fall within the scope of the appended claim.

Having described the invention what is claimed is:—

The combination with a hair clipping device, of a base plate, a plurality of right angularly disposed spaced blades carried thereby, said blades having convex outer surfaces terminating in a forwardly pointed 80 end which extends from the rear end of the teeth of the clipping device to the rear edge of the base plate and spaced pairs of relatively short curved blades located between the first mentioned blades. 85

In testimony whereof I affix my signature.

FOREST L. GRAY.
